NAILING MACHINE

John P. Nelson, Wausau, Wis.

Application October 12, 1942, Serial No. 461,742

3 Claims. (Cl. 1—46)

The present invention relates to new and useful improvements in portable nailing machines, particularly for securing the light stops in doors with conventional brads, although it will be understood, of course, that the device may be used for any other purpose for which it may be found adapted.

An important object of the invention is to provide, in a manner as hereinafter set forth, a machine of the aforementioned character comprising common means for manually actuating a driving hammer and for automatically feeding the brads, one at a time, to said hammer.

Another very important object of the invention is to provide a machine of the character described comprising a feed mechanism embodying a novel construction and arrangement whereby jamming will be substantially prevented.

Other objects of the invention are to provide a nailing machine which will be comparatively simple in construction, strong, durable, highly efficient and reliable in use, compact, light in weight, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a machine constructed in accordance with the present invention, showing the device in use.

Figure 2 is a top plan view of the machine.

Figure 3 is a view principally in vertical longitudinal section, taken substantially on the line 3—3 of Figure 2, showing the machine in use.

Figure 4 is a cross-sectional view through the machine, taken substantially on the line 4—4 of Figure 1.

Figure 5 is a cross-sectional view, taken substantially on the line 5—5 of Figure 3.

Figure 6 is a view in vertical section through the feed mechanism, taken substantially on the line 6—6 of Figure 1.

Figure 7 is a vertical sectional view, taken substantially on the line 7—7 of Figure 6.

Figure 8 is an enlarged fragmentary view in vertical section through the upper portion of the brad elevator and adjacent parts.

Figure 9 is a cross-sectional view, taken substantially on the line 9—9 of Figure 1.

Figure 10 is a view in vertical longitudinal sec-

tion through the gun, taken substantially on the line 10—10 of Figure 2.

Referring now to the drawings in detail, it will be seen that the embodiment of the invention which has been illustrated comprises a base 1. The base 1 includes an inverted, longitudinal channel bar 2 which terminates in an upturned forward end portion constituting a post 3. The base 1 further includes a crosshead 4 on the forward portion of the bar 2. Mounted for vertical adjustment beneath the crosshead 4 is a shoe 5. As best seen in Figure 5 of the drawings, bolts 6 are anchored in the shoe 5 and extend slidably through the crosshead 4. Coil springs 7 are engaged with nuts and washers 8 on the bolts 6 for yieldingly urging the shoe 5 upwardly beneath the crosshead 4 and the bar 2. Adjusting screws 9 are threaded through the end portions of the crosshead 4 and engaged with metallic plates 10 on the shoe 5 for raising or lowering the forward end of the machine on the work. A removable bar 11 is secured longitudinally at 11' beneath the bar 2 rearwardly of the shoe 5. The elements 5 and 11 are adapted to slidably support the machine on the members 12 of a conventional door 13. The usual stops for the lights 14 of the door 13 are indicated at 15. Bars 11 of any desired length may be used for extending the length of the base structure 1 as may be necessary to bridge various spaces between the members 12 of the work.

Mounted for swinging movement in a vertical plane on the base 1 is a gun 16. The gun 16 includes a forwardly inclined, dovetail guide 17 which is pivotally mounted at 18 on the rear end portion of the bar 2. Projecting forwardly and downwardly from the guide 17, adjacent one side of the bar 2, is an arm 19. A barrel 20 is mounted on the forward end portion of the arm 19. Threaded into the forward end portion of the barrel 20 and adapted to be pressed against the stop to be secured is a nose 21. Rising from the nose 21 is a feed tube 22 which communicates with the bore 23 of said nose. The feed tube 22 tapers toward its lower end. Projecting at an inclination from the upper end of the feed tube 22 is a forwardly directed lip 24, the purpose of which will be presently set forth. The bore 23 of the nose 21 is closed adjacent its forward end by a gravity actuated ball 25.

The gun 16 further includes a metallic block 26 which is slidable on the guide 17. An operating handle 27 rises from the block 26. Depending from the block 26 is a pin 28 which is operable in a longitudinal slot 29 which is provided there-

for in the guide 17. A coil spring 30 has one end connected to the pin 28 and its other end connected to a plate 31 on the rear of the guide 17 for retracting the block 26.

Fixed on one side of the block 26 is a guide 32. The stem 33 of a hammer or plunger 34 extends slidably through the guide 32, said plunger being operable in the barrel 20. Projecting from the head 34 of the plunger is a pin 35 which is operable in the bore 23 of the nose 21 for ejecting therefrom a brad 36 for driving said brad past the ball 25 into the work. The driving stroke of the plunger 34 and consequently the set of the brad in the work may be regulated as desired through the medium of nuts 37 which are threaded for adjustment on the rear end portion of the stem 33. A coil spring 38 encircles the stem 33 and has one end engaged in the guide 32 and its other end engaged with the head of the plunger 34 for actuating said plunger on its driving or power stroke. A shock absorbing washer 39 is provided on the plunger stem 33 between the guide 32 and the nuts 37.

Pivotedly mounted at 40 (Figure 10) for swinging movement in a vertical plane on the barrel 20 is a latch 41. The latch 41 comprises, at an intermediate point, a lug or finger 42 which extends through an opening into the barrel 20 for engagement with the plunger 34 for releasably securing said plunger against actuation by the coil spring 38. At its free end, the latch 41 is beveled in a manner to provide a cam 43 which is adapted to ride up on the portion 44 of the guide 32 when the handle 27 is moved forwardly for releasing the plunger 34 after the tension of the coil spring 38 has been built up. Mounted on the side of the bar 2 which is remote from the arm 19 is a keeper 45. The keeper 45 is engageable over a roller 46 (see Fig. 2) which is rotatably mounted on the adjacent side of the block 26 for positively preventing upward swinging movement of the gun 16 except when the slidable elements thereof are in retracted position.

Removably mounted on the upper portion of the post 3 and projecting rearwardly therefrom is a stationary shaft 47. A stationary disk 48 is removably secured on the rear end portion of the shaft 47. Rotatably mounted on the shaft 47 is a drum 49 which encircles the disk 48 in spaced relation to the periphery thereof, said drum including a front plate 50. Fixed on the plate 50 is a hopper 51 for the reception of a supply of conventional brads. Toward this end, the hopper 51 is provided with a pivoted closure 52. A ratchet gear 53 is fixed on the front of the hopper 51 and rotates on the shaft 47.

Journaled for swinging movement on the shaft 47, between the ratchet gear 53 and the post 3, is an arm 54. A lever 55 is pivotally mounted on the lower portion of the post 3. A rod 56 operatively connects the slidable block 26 to the free end portion of the lever 55. An adjustable link 57 operatively connects the lever 55 to the arm 54. A pawl 58 on the arm 54 is engaged by a spring 58' with the ratchet gear 53 for intermittently rotating the hopper 51 and the drum 49. A spring pressed dog 59 on the post 3 below the shaft 47 is engaged with the ratchet gear 53 for preventing retrograde rotation of the hopper 51 and the drum 49. It will thus be seen that the hopper 51 and the drum 49 are operatively connected to the manually operable handle 27 for rotation thereby in a step-by-step fashion.

Mounted in the drum 49 for rotation therewith is a brad elevator 60 comprising a ring 61 which

is fixed on the plate 50. The disk 48 closes the rear end of the ring 61. The ring 61 includes a peripheral flange 62. Immediately adjacent the flange 62, the ring 61 has formed therein a plurality of circumferentially extending, spaced slots 63 for the reception of the brads, as at 64. It will be observed that the slots 63 are of a width to prevent the passage of the heads of the brads 64. The hopper 51 communicates with the interior of the brad elevator 60 through an opening 65 in the plate 50. Thus, when the opening 65 is in lowered position, the brads flow by gravity into the elevator ring 61 from the hopper 51. A circumferentially extending return chute 66 is provided on the hopper 51 for excess brads that may be deposited in the elevator ring 61. The return chute 66 communicates with the elevator 60 through an opening 67 in the plate 50 which is located at a point substantially diametrically opposite the opening 65.

Fixed in the rear portion of the drum 49 is an internally toothed, annular ratchet 68. At circumferentially spaced points, the rear portion of the drum 49 is struck inwardly in a manner to provide cams 69. Between the cams 69, pins 70 project rearwardly from the periphery of the drum 49. The purpose of the members 68, 69 and 70 will also be presently set forth.

As illustrated to advantage in Figures 5, 7 and 8 of the drawings, a vertical tube 71 is mounted on the upper front portion of the disk 48. A passage 72 in the disk 48 communicates with the tube 71 at its lower end. Projecting laterally from the upper portion of the tube 71 is a pair of wings 73. A pivoted, spring pressed plate 74, operable between the wings 73, constitutes a yieldable upper wall portion for the tube 71. A suitable spring 75 yieldingly engages the plate 74 with the ring 61. Also mounted on this portion of the disk 48 is a resilient double hook 76 which rides on the ring 61 above the tube 71. As the elevator 60 carries the brads 64 upwardly in the slots 63 of the ring 61, the double hook 76 engages the heads of said brads, causing them to be turned over as the ring 61 rotates, said brads dropping out of said slots 63 into the tube 71. The pivotally mounted, spring pressed plate 74 permits any of the brads which may escape the member 76 to pass without jamming or damaging the machine. An arcuate tongue 77 extends downwardly from the upper portion of the tube 71 and constitutes an auxiliary support for guarding the resilient member 76 against breakage. Mounted on the rear of the disk 48 for receiving the brads 64 from the tube 71 through the passage 72 is a magazine 78. The magazine 78 includes an inclined chute 79 comprising a vibrating lower wall 80 having its lower end portion pivotally secured, as at 81. A guide 82 on the disk 48 directs the brads into the chute 79 from the passage 72. A guard 83 extends over the guide 82 from the upper portion of the chute member 80. A chute 84 extends from the upper portion of the chute 79 through the disk 48 for returning excess brads to the elevator 60.

Mounted on a bracket 85 on the upper portion of the vibrating chute wall 80 is a clock spring 86. The spring 86 comprises a free outer end portion which projects into the path of the pins 70 for periodically winding and releasing said spring for vibrating the chute wall 80.

Mounted for horizontal movement on the back of the disk 48 above the shaft 47 is a substantially U-shaped slide 87. A lever 88 is pivotally mounted at an intermediate point, as at 89, on the rear

of the disk 48 above the slide 87. On one end of the lever 88 is a shoe 90 which is engageable by the cams 69 for periodically actuating said lever. A rod 91 has one end pivotally connected to the other end portion of the lever 88 and its other end portion extending slidably through one of the legs of the substantially U-shaped slide 87. A coil spring 92 on the rod 91 yieldingly connects the slide 87 to the lever 88 for actuation in one direction thereby. An adjustable stop screw 93 in the other leg of the slide 87 is engageable with the lever 88 for returning said slide. A finger 94 on the slide 87 is engageable with the upper end portion of the vibrating chute wall 80 for holding same in open position until just before the pins 70 clear and free the vibrating spring 86. Thus, binding of the brads in the chute 79 is prevented.

The magazine 78 further comprises a stationary plate 95 which extends horizontally from the back of the disk 48 at the lower end of the chute 79. The plate 95 has formed therein a slot 96 for the passage of the brads from the chute 79. Mounted beneath the plate 95 in spaced relation thereto is a bottom plate 97. One end only of the plate 97 is secured to the plate 95, as at 98. Slidably between the plates 95 and 97 is an ejector 99. A spring 100, which is also secured by the bolt 98, yieldingly urges the members 97 and 99 upwardly beneath the plate 95. The ejector 99 projects from one end of the plates 95 and 97 and has formed therein a longitudinal slot 101. The slot 101 accommodates an operating lever 102 which is pivotally suspended at 103 on the back of the disk 48. A thumb nut 104 is provided for frictionally securing the lever 102 against swinging movement on its pivot 103 when desired, as when the machine is being loaded. A coil spring 105 yieldingly connects the ejector 99 to the lever 102 for actuation thereby. Mounted on the ejector 99 is a substantially U-shaped bracket 106 which bridges the slot 101. Mounted for sliding adjustment on the bracket 106 is a stop 107 which is engaged with the lever 102 for adjusting the position of said lever relative to the ejector 99. A screw 108 is provided on the bracket 106 for adjusting the stop 107.

Mounted laterally on the free end portion of the lever 102 is a roller 109 (see Fig. 3). The roller 109 is also engageable by the cams 69 for actuating the ejector 99 in a manner to discharge from the magazine 78 the lowermost brad of the column of brads in the chute 79. A return spring 110 for the lever 102 and the ejector 99 is connected to the adjacent end portion of the lever 88.

Pivottally mounted on the magazine 78 is a dog 111 which is operable by the annular ratchet 68. Pivottally mounted on the magazine 78 below the member 111 is a lever 112. A link 113 connects one end of the lever 112 to the dog 111. Mounted on the other end portion of the lever 112 is a screw 114 which is adapted to strike beneath the adjacent end portion of the plate 95 for vibrating same in a manner to further prevent jamming of the brads in the magazine. A coil spring 115 connects said other end portion of the lever 112 to the dog 111. From the foregoing it will be seen that when the dog 111 is swung upwardly by one of the teeth of the ratchet 68, the lever 112 is actuated in a direction to swing the screw 114 away from the plate 95 and tension the spring 115. Thus, when the dog 111 is released, the spring 115 causes the screw 114 to strike the plate 95 a sharp blow. From the foregoing it will

be observed that the elements 112 and 114 constitute what may be considered a vibrating hammer.

The outer vertical side plate 116 (Figures 3 and 5 4) of the magazine 78 has formed therein an opening 117 for access to the chute 79. A spring pressed closure 118 for the opening 117 is pivotally mounted on the plate 116. The closure 118 is slidable on its pivot 119 toward and away from the plate 116. A spring 120 on the pivot 119 yieldingly engages the closure 118 with the plate 116.

The ejector 99 deposits the brads in an inclined trough 121 which depends from the magazine 78. 15 Pivottally mounted on the lower end portion of the trough 121 and adapted to receive the brads therefrom is a discharge nozzle 122. The nozzle 122 is adapted to be swung downwardly for discharging the brads into the tube 22 of the gun 16. 20 A return spring 123 is provided for the nozzle 122. The pivot 124 of the nozzle 122 also carries a substantially U-shaped closure 125 for said nozzle. A return spring 126 connects the closure 125 to the nozzle 122.

25 Projecting from the right portion of the closure 125 is a stop pin 127 which is engageable with the lip 24 on the tube 22 for arresting said closure 125 for opening the nozzle 122, as said nozzle continues across the mouth of said tube 22, at which 30 time the spring 126 is tensioned.

35 Fixed on the pivoted end of the nozzle 122 is a depending arm 129. Mounted on the operating rod 56 is a bracket 130. Pivotally mounted on the bracket 130 is a pawl 131. A stop lug 132 on the bracket 130 positively limits swinging movement of the pawl 131 in one direction. A return spring 133 is connected to the pawl 131.

40 It is thought that the operation of the machine will be readily apparent from a consideration of the foregoing. Briefly, when the handle 27 is pushed forwardly and downwardly, the coil spring 38 is compressed by the guide 32. This continues until the portion 44 of the guide 32 engages the cam 43 of the latch 41 and raises said latch, 45 thereby freeing the plunger 34. When thus released, the plunger 34 is actuated by the spring 38 for driving the brad 36 into the work. As hereinbefore mentioned, the set of the brad may be regulated as desired through the medium of the adjustable nuts 37. The handle 27, the plunger 34, et cetera, are then retracted and the latch 41 again drops to operative position. The machine is then moved to its next position on the door. The gun 16 may be readily swung upwardly on the pivot 18 sufficiently to clear cross members on the door. However, this is positively prevented by the engagement of the keeper 45 with the roller 46 while the block 26 is in its forward or projected position.

50 55 60 65 70 75 When the handle 27 is moved forwardly, the drum 49 with the hopper 51 thereon is rotated one step in a clockwise direction through the elements 56, 55, 57, 54, 58, et cetera. When the opening 65 in the plate 50 is disposed downwardly, the brads flow by gravity from the hopper 51 into the elevator 60. The rotary movement of the drum 49 and the jarring action of the hammer 16 causes these brads to slip by gravity through the slots 63 in a manner to be suspended by their heads on the ring 61. The brads are thus carried upwardly until they reach the position shown to advantage in Figure 8 of the drawings where they are deposited in the tube 71 by the member 76 in the manner hereinbefore described. Headless brads which slip through the slots 63 are dis-

charged from the machine through an outlet 134 which is provided therefor in the periphery of the drum 49. Excess brads which may enter the elevator 60 are returned to the hopper 51 through the circumferentially extending chute 66 when the opening 67 in the plate 50 reaches its lowered position. The brads drop by gravity in the tube 11 and are deposited in the chute 79 of the magazine 78. These brads are discharged, one at a time, with each stroke of the lever 102 into the trough 121 by the slideable ejector 99.

The nozzle 122 is normally held in its raised position out of communication with the tube 22 by the spring 123. In this position, the nozzle 122 is held in closed position in the closure 125 by the spring 126. Upon forward movement of the rod 56 with the handle 27, the spring 133 permits the pawl 131 to swing in a manner to pass the arm 129. However, on the return movement of the rod 56, the pawl 131 engages the stop lug 132 under the influence of the spring 133 and is arrested thereby. Thus, the pawl 131 engages the arm 129 and swings the nozzle 122 downwardly, together with the closure 125. The closure 125 is arrested by the engagement of the pin 127 with the lip 24 on the tube 22 but the nozzle 122 continues to a position over said tube. Thus, the nozzle 122 is opened and the brad therein drops into the tube 22 and is deposited in the bore 23 of the nose 21 of the gun.

The pawl 131 on the now returning operating rod 56 then clears and releases the arm 129 for permitting the spring 123 to return the nozzle 122 to its raised position, during which movement the closure 125 is returned to operative position on said nozzle by the spring 126. The bracket 130 is secured on the rod 56 by screws 128. The construction is such that the bracket 130, with the pawl 131 thereon, may be readily adjusted on the rod 56 relative to the arm 129.

It is believed that the many advantages of a portable nailing machine constructed in accordance with the present invention will be readily

understood, and although a preferred embodiment of the device is as illustrated and described, it is to be understood that changes in the details of construction and in the combination and arrangement of parts may be resorted to which will fall within the scope of the invention as claimed.

What is claimed is:

1. A nailing machine comprising a base slidably engageable on a piece of work, a driving gun pivotally mounted for swinging movement in a vertical plane on the base, said gun including 10 slideable operating means, means for securing the gun against swinging movement on the base when the operating means is in one position, and means on the base operable by said operating means for feeding brads to the gun.

2. A nailing machine comprising a base, a guide pivotally mounted on said base, an arm on said guide, a barrel mounted on said arm, a driving 20 plunger operable in the barrel, a coil spring for driving said plunger, manually operable means slideable on the guide for tensioning the spring and for disengaging the latch from the plunger, means for releasably securing the guide against 25 swinging movement on the base when the first-named means is in one position, and means on the base operable by said first-named means for feeding brads to the barrel.

3. A nailing machine comprising a base, a driving 30 gun mounted on said base, a stationary disk mounted on the base, a hopper for the reception of brads rotatably mounted on the base, a drum rotatable on the base with the hopper and communicating therewith for receiving brads therefrom, a vibrating magazine mounted on the disk, a rotary elevator for the brads in the drum, means for delivering the brads by gravity from 35 said elevator to the magazine, coating means on the magazine and the drum for vibrating said magazine, and means for delivering the brads from the magazine to the gun.

JOHN P. NELSON.
